UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A HANDLE FOR SPOONS, &c.

SPECIFICATION forming part of Design No. 29,356, dated September 20, 1898.

Application filed August 17, 1898. Serial No. 688,817. Term of patent 7 years.

To all whom it may concern:

Be it known that I, CHARLES OSBORNE, a citizen of the United States, residing in the city, county, and State of New York, have invented and produced a certain new and original Design for Handles for Spoons or Similar Articles, of which the following is a specification, reference being had to the accompanying drawings, forming part thereof.

Figure 1 is a view of the obverse, and Fig. 2 is a view of the reverse, side of a handle, showing my design.

The leading features of my design are the fiddle-shaped head having the outline of the upper portion in short waves or scallops and a slender shank fluted or reeded, with its lower portion swelled and waved in outline, the whole ornamented with scrolls, shells, leaves, and ribbons in relief combined in that style of ornamentation generally known as "rocaille" or "rococo." In obverse the widened upper scalloped part of the head is nearly filled with such ornament gracefully arranged and the narrow part bordered by slender scrolls is plain, excepting a narrow ribbon just within the scrolls. The head widens again to join the shank and is bordered at this portion by shorter reversed scrolls partly inclosing a foliate ornament reaching downward to a shell flanked by scrolls at the upper end of the shank. The latter is fluted or reeded and is ornamented with a flowing ribbon on each side extending part way down the shank, the reeds showing between the curves of the ribbon. The lower end of the shank is waved in outline to correspond to the head and is similarly orna-

mented by a shell surmounted by a single central scroll and reversely-arranged side scrolls. The reverse is practically the same as the obverse, but with the ornamentation and tracery in lower relief. At the junction with the bowl, prongs, or blade at the extreme lower end of the shank is added a large shell-like ornament, above which are conventional leaves pointing downward between the lower pair of scrolls.

By reason of the general shape of the handle it lends itself with more than ordinarily pleasing effect to this adaptation of the rococo ornament, which, while rich and profuse, is well balanced and tasteful.

Although I have shown the handle as applied to a spoon it will be understood that the design is also intended for the handles of forks, knives, and similar articles of table flat ware.

I claim—

1. In a design for a handle for spoons or similar articles, the obverse as herein shown and described.
2. In a design for a handle for spoons or similar articles, the reverse as herein shown and described.
3. The design for a handle for spoons or similar articles, herein shown and described.

In testimony that I claim the invention above set forth I affix my signature in presence of two witnesses.

CHARLES OSBORNE.
